UNITED STATES PATENT OFFICE

VINCENZO BAFARO, OF NEW YORK, N. Y.

AMUSEMENT DEVICE

Application filed October 1, 1930. Serial No. 485,768.

This invention relates to an amusement device constructed for the use of children although capable of being used by adults when made to the proper size.

5 The object of the invention is to provide a steerable support capable of being propelled while in the water, the structure being such that some skill on the part of the operator is needed to keep the device in an upright position and moving in the direction desired.

10 Another object of the invention is to provide a steerable float capable of use by one person and formed with means capable of being propelled by the legs of the person 15 using the device.

15 A further object, more specifically, is to provide an amusement device to be used by bathers, the structure being such as to present a float capable of supporting all parts 20 of the body of the person using the float while propelling the person from place to place.

In the accompanying drawings—
25 Figure 1 is a longitudinal vertical sectional view through the amusement device disclosing an embodiment of the invention;

Figure 2 is a top plan view of the invention shown in Figure 1;

Figure 3 is a bottom plan view of the device shown in Figure 1;

30 Figure 4 is a sectional view through Figure 1 on the line 4—4.

Referring to the accompanying drawings by numerals, 1 indicates a casing which is preferably substantially tubular with a round 35 rear end and a pointed front end and with a flat bottom, as shown in Figure 4. The casing 1 is preferably divided into a lower section 2 and a top section 4 which may be connected together in any desired manner, 40 for instance, by screws or straps.

Arranged interiorly of the casing 1 are air compartments 5, 6, 7 and 8, compartments 5 and 6 being at the front and compartments 7 and 8 being at the center of the rear.

45 Between the front and rear compartments is provided a space 9 which may be watertight if desired, or may be open to the water. In this compartment there is arranged a large bevel gear 10 rigidly secured to a shaft 11 50 which shaft extends through the casing 1

so that the crank arms 12 and 13 may be rigidly secured thereto. Each of these arms carries a chain 14, and each chain carries a stirrup 15 whereby when a person is sitting on the seat 16 he may place his feet in the respective stirrups 15 and rotate the shaft 11, and consequently rotate the gear wheel 10.

55 Shaft 11 is carried by a central support 17 and by an enlargement 18 and 19 formed integral with the casing 1 or rigidly secured thereto. A longitudinally positioned drive shaft 20 is also journaled in the fitting 17 and carries a pinion 21 which continually meshes with the gear wheel 10. From this it will be seen that whenever shaft 11 is rotated gear 60

65 wheel 10 will be rotated and also pinion 21 and shaft 20. Shaft 20 is supported by suitable bearings 22 and at the outer end carries a propeller 23 which extends to the rear so as to be free from the casing 1 and free of the 70 rudder 24. As propeller 23 is moved, the casing and all parts carried thereby will be moved forward through the water. This includes the person sitting on seat 16. The rudder 24 is operated by suitable cables 25 and 75 26, as shown in Figure 2, said cables being connected with handle bars 27 pivotally mounted at 28 on the casing 4.

75 From this it will be evident that the person sitting on the seat 16 may use his feet to operate the stirrups 15 and thereby cause the propeller 23 to rotate. While he is doing this he may manipulate the handle bars 27 for steering the device.

80 Preferably the device is made of a size to be almost submerged when the person is using the same, so that the propeller 23 will have ample water on which to act.

85 From Figure 4 it will be noted that the casing 1 is flat at the bottom. This assists the 90 person using the device in holding it upright. However, in order to add better balance or steadyng means, slides 29 and 30 are provided. Each of these slides is provided with a pair of extensions 31 operating on guide 95 rods 32 and 33. Each of the plates 29 and 30 are also provided with one or more slots 34 through which clamping thumb screws 35 extend. Ordinarily the plates 29 and 30 are 100 in the position shown in Figure 3 but when

the device is to be used they are substantially outward to the position shown in Figure 3 and then the thumb screws are tightened. This will give side fins which act to prevent rolling of the device.

It will be understood that numerous slight changes and rearrangement of the parts may be resorted to without departing from the spirit of the invention. However, it is to be noted that the invention includes some form of buoyancy for the device and also a driving and steering mechanism which may be easily operated by the person using the device, even though that person is but a mere child. Where the device is used by a small child it may be used in water which is only deep enough to reach the child's waist. Consequently, whenever the device upsets the child may readily stand up and thus be safe against drowning.

I claim—

1. An aquatic amusement device including a casing, buoyancy tanks arranged in the casing, manually actuated means including stirrups and crank arms for propelling the casing, means for steering the casing, and a plurality of sliding plates carried by the bottom of the casing adapted to be moved inwardly and outwardly as desired for producing a more-or-less anti-rolling action.

2. An amusement device including a casing, buoyancy tanks arranged in the casing, means for propelling the casing, means for steering the casing and a pair of sliding plates carried by the bottom of the casing, each plate having a slot therein, a clamping screw for each slot, and means for actuating said plates to an outer and inner position, said screws acting to clamp said plates in either position.

3. An aquatic amusement device including a casing, a pair of buoyancy tanks arranged in front of the casing, a pair of buoyancy tanks arranged in the rear of the casing, there being a chamber left between said pairs of buoyancy tanks, a driving shaft extending transversely through said chamber, a gear rigidly secured to said driving shaft, a pinion meshing continually with said gear wheel, a driving shaft rigidly connected with said pinion and rotated thereby, a propeller carried by said shaft and rotated thereby, a crank arm arranged on each end of said first mentioned shaft, a chain depending from the outer end of each of said crank arms, a stirrup connected at the free end of each of said chains, and means for steering the device.

4. An aquatic amusement device including a casing, buoyancy tanks in the casing, means for controlling the casing, said means including a power shaft extending transversely through the casing, a crank arranged at each end of said shaft, a chain connected

with the outer end of each of said cranks, a stirrup connected at the lower end of each of said chains, a seat for the operator positioned so that the feet of the operator may engage said stirrup, and means for steering the device.

5. An aquatic amusement device including a casing, a pair of buoyancy tanks arranged in front of the casing, a pair of buoyancy tanks arranged in the rear of the casing, there being a chamber left between said pairs of buoyancy tanks, a driving shaft extending transversely through said chamber, a gear rigidly secured to said driving shaft, a pinion meshing continually with said gear wheel, a driving shaft connected with said pinion and rotated thereby, a propeller carried by said shaft and rotated thereby, a crank arm arranged on each end of said first mentioned shaft, a stirrup connected at the free end of each of said crank arms, and means for steering the device.
